C. A. ERICKSON

CHECK NOTCHER

Filed Jan. 11, 1928

Inventor:

Charles A. Erickson

by Albert Scheibh
Attorney

UNITED STATES PATENT OFFICE.

CHARLES A. ERICKSON, OF CHICAGO, ILLINOIS.

CHECK NOTCHER.

Application filed January 11, 1928. Serial No. 245,866.

My invention relates to devices for notching an edge portion of a rupturable material, as for example a charge-indicating edge portion of a sales check of the class commonly used in lunch rooms and restaurants.

In its general objects, my invention aims to provide a notching device of this class in which the casing and the notching member are each formed of sheet material and slideably interfit each other; in which these two parts are shaped to prevent rotation of the notching member in the casing, and also are shaped for producing a relatively long and narrow notch in a sales check or the like; and in which these two parts have integral portions disposed for operatively retaining a spring which retracts the notching member, and for limiting the movement effected by the spring.

Furthermore, my invention aims to provide a construction which will permit of the speedy and inexpensive manufacture and assembly of the device, which will facilitate the ejecting of the check portions severed by the device, and which will permit the ready removal of such detached portions or clippings in case they should enter the bore of the notching member. Moreover, my invention aims to provide a notching device in which the casing member can readily be made of a metal which is suitable for the body (and desirably also for the resilient pad-locking tongue) of a combined check-holder and notcher, thereby adapting my notching device for the combination device more fully disclosed as to its other features in my copending application No. 245,865 on a sales check holder, as filed January 11, 1928.

More particularly, my invention provides a check-notcher casing formed by suitably rolling up a previously perforated sheet metal strip to afford a tubular casing of a suitable (and preferably non-circular) transverse section, and provides integral portions which interlock to retain the casing in its said sectional shape. It also provides a notching member so formed of a single strip of sheet metal as to slidably and non-rotatably fit such a casing, and provided with an integral head whereby the notching member may be slid in one direction in the casing. Furthermore, my invention provides integral means on the casing for engaging one end of a spring which has its other end engaging a part of the notching member (desirably the head of the latter) for retracting that member, and

provides the notching member and the casing with interengageable portions disposed for limiting the movement of the notching member by the spring. It also provides an arrangement in which the spring is held clear of the exit opening through which the severed check portions or clippings are detached from the casing, in which these severed portions are deterred from entering the bore of the notching member, and in which the notching member normally presents an opening disposed for inserting a pin or other instrument for clearing the bore of the notching member.

Still further and also more detailed objects will appear from the following specification and from the accompanying drawing, in which

Fig. 1 is a front elevation of the lower portion of a combined sales check-holder and notcher which includes an embodiment of my invention.

Fig. 2 is an enlarged end elevation, taken from the left side of Fig. 1.

Fig. 3 is a rear elevation, drawn on the same scale as Fig. 1.

Fig. 4 is an enlarged view, looking upward from the bottom of Fig. 1.

Fig. 5 is an enlarged vertical section, taken along the line 5—5 of Fig. 2, with the notching member in its normal or retracted position.

Fig. 6 is an enlarged perspective view of the notching member.

Fig. 7 is a correspondingly enlarged perspective view of the blank from which the notching member of Fig. 6 was formed.

Fig. 8 is a plan of the blank from which the notcher casing member of Figs. 1 to 5 was formed.

In the illustrated embodiment, Figs. 1 to 4 show portions of a combined sales check holder and notcher, of the type described in my said copending application, in which the pad of checks 1 rests on a holder portion 2 which is formed of the same strip of sheet material with the casing of my notching device. For this purpose, the original sheet metal blank includes as an extension of the holder portion 2 the series of metal parts for which the fold lines are indicated by dotted lines in Fig. 8, in which figure the line A denotes a lower end of a holder portion 2. These parts are proportioned for affording a tubular casing which includes a front side 3, forwardly and rearwardly inclined sides 4 and 5 disposed at an acute angle to each other and adjoined on

a line B which extends medially across a substantially diamond-shaped aperture 26 in the metal blank, a rear side 6, and a top side 7 adjoined at a line C to another holder part 8.

5 When the part of the blank shown in Fig. 8 is rolled up to dispose its several sections as just recited, the holder parts 2 and 8 overlap as shown in Fig. 2 and are suitably secured to each other—as for example, by fingers 9 extending from opposite edges of the holder section 2 of the blank and clinched over the edges of the holder section 8.

10 The notching member is formed from a blank shaped as in Fig. 7, so that when folded approximately along the dotted lines of this figure, the blank will form a tube having a front 10 adjoined to a back 11 at an acute angle, a top 12, and a head 13 bent from one end of the back 11 to overhang the adjacent end of 15 the front 10. The ends of the back and front which are directed away from this head have portions 12 oblique to the bend line D at which these notcher walls are connected in an acute angled formation, the slope of the ends 20 of 12 being here shown as corresponding to that of the walls of the aperture 26 beyond 25 which the notcher is normally retracted.

To retract the notcher, I provide a compression spring 23 which extends through the bore of the tubular notching member and through that end portion of the casing toward which the sloping ends 12 of the notching member face. This spring bears at its other end against a suitable thrust formation on the casing, here shown as a thrust arm 14 bent inwardly from the adjacent end of the back of the casing. The bore of the notcher only needs to be slightly larger than the diameter of the spring in the direction in which the top 12 of the notcher extends, but is considerably wider (in the general direction of the front 10 and back 11), so that the lower end of the spring if adjacent to the top 7 of the casing will be spaced by a considerable distance 30 from the acute edge of the casing through which the notch 6 extends. To permit such an approach to the top of the casing, I preferably have the top 12 of the notching member extend only for part of the length of this member from its head. Then I provide the arm 14 at its inner end with a guard finger 15 which extends between the spring and the acute or wedge-shaped edge of the casing to keep that end of the spring away from the 35 said acute edge. By doing this, I leave a clear end opening (as shown in Fig. 2) for the ejection of the check portions or clippings severed by the notcher.

I also provide means for limiting the extent to which the notching member is slid away from the thrust arm 14, such as a stop finger 16 formed on the end of the front casing side 4 which is nearest the head of the notcher, this finger being bent inwardly of 40 the casing so as to be engaged by the inner end

of a recess 17 in the adjacent side 10 of the notching member. This recess is so proportioned to the length of the notching member, the location of the lateral notch or aperture 26, and the length of the spring, that the oblique ends of the notching member (which form cutting edges) are normally retracted by the spring beyond the aperture 6, as shown in Fig. 5.

50 In using my notching device, the selected edge portion of the detached check is inserted in the aperture 26 which forms a lateral open notch in the casing, and the notching member is slid against the resistance of the spring, thereby causing edges of the said aperture to 55 cooperate with the ends of the sides 10 and 11 of the notching member to shear out a triangular edge portion of the check. The upper ends of the aperture 26 are preferably spaced farther from the top 7 of the notcher casing 60 than the guard finger 15, so that the severed check portion is smaller than the triangular end opening adjacent to this guard finger, and the converging edge parts of the severed check portion have the cutting edges of the 65 notching member engaging them. Consequently, the operating movement of the notching member first cuts out a small edge portion of the check and then forces this check clipping between the guard finger 15 and the acute edge of the bore of the casing, and the successively superposed check clippings force one another out of the casing. 70 However, in case an improper manipulation of my device should cause any detached check 75 clippings to enter the bore of the notching member, these can easily be ejected by inserting a pin or the like through the normally exposed aperture formed between the head 13 and the adjacent end of the casing by the 80 notch 17. Hence this notch affords the double purpose of permitting the stop finger 16 to be effectively disposed and of facilitating the 85 removal of check clippings in case such clippings should enter the bore of the notching 90 member.

95 Since the stop finger 16 can readily be bent inwardly to its operative position after the spring and the major portion of the notching member have been inserted into the casing, 100 the entire assembling of my device is exceedingly simple. The use of single-piece blanks for the casing and for the notching member also eliminates the need of any auxiliary fastening members, so that the entire cost of my 105 device is quite low.

110 In employing my notching device on a check holder, I desirably dispose it with the wedge-shaped and apertured edge directed 115 away from the main portion of the holder, as shown in Figs. 1 to 3. However, I do not wish to be limited in this respect, nor to the 120 mounting of my device on a holder which supports the materials that are to be notched by it. Neither do I wish to be limited to the 125 130

details of construction and arrangement which I have described in connection with an illustrative embodiment of my invention, since many changes might obviously be made 5 without departing either from the spirit of my invention or from the appended claims.

I claim as my invention:

- 10 1. A check notcher comprising a tubular casing having an aperture in its side, a notching member slidable in the casing and normally having its inner end clearing the said aperture, the notching member having a recess in a wall thereof near its outer end and the casing having an inwardly directed projection at the opposite end from that adjacent to the said recess, a compression spring interposed between the said projection and the notching member, and a finger on the housing projecting into the recess and normally engaging an edge of the recess to limit the sliding of the notching member by the spring.
- 15 2. A check notcher comprising a tubular casing having a notch in one side and having inwardly directed fingers above and below the said notch, a notching member slidable in the casing and having an aperture into which the upper finger extends, and a compression spring interposed between the lower finger and the notching member.
- 20 3. A check notcher comprising a tubular casing having a notch in one side and having inwardly directed fingers above and below the said notch, a notching member slidable in the casing and having a recess into which the upper finger extends, and a compression spring interposed between the lower finger

and the notcher; the lower finger being of such a size as to expose an end opening of the casing in longitudinal alinement with the said notch, and the lower finger being formed 40 for holding the lower end of the spring clear of the opening thus exposed.

4. A check notching device comprising a tubular casing of polygonal bore section presenting a sharp angle between two adjacent 45 sides and having a lateral notch extending across the said angle adjacent to one end of the casing, the casing having at the said end a finger extending toward the apex of the said angle from the opposite side of the casing, a 50 tubular notching member slidably fitting the bore of the casing and having a freely open end adapted to slide freely over the said finger, the notching member having a head closing its other end; and a compression spring 55 interposed between the finger and the said head; the finger terminating at a distance from the apex of the said angle to leave a clear space for the exit of clippings sheared by the notching member from checks inserted 60 in the said notch from the exterior of the casing.

5. A check notching device as per claim 4, in which the finger has at its free end a finger 65 extending toward the said head of the notching device and extending between the spring and the apex of the said angle to retain the spring on the finger.

Signed at Chicago, Illinois, January 7, 1928.

CHARLES A. ERICKSON.
